UNITED STATES PATENT OFFICE.

HARRY J. MARKS, OF NEW YORK, N. Y.

MOTOR-VEHICLE.

SPECIFICATION forming part of Letters Patent No. 706,978, dated August 12, 1902.

Application filed September 25, 1901. Serial No. 76,500. (No model.)

To all whom it may concern:

Be it known that I, HARRY J. MARKS, a citizen of the United States, residing at New York, State of New York, have invented certain new 5 and useful Improvements in Motor-Vehicles, of which the following is a clear, full, and exact description.

My invention relates to an improvement in motor-vehicles; and one of my objects is to 10 provide a construction by which the motor is hung from the vehicle on a pivot, at one side of the center of gravity thereof, and is spring-supported, whereby it may vibrate on said pivot when the vehicle passes over inequalities 15 in the road, by which the motor is relieved of sudden shocks.

Another object of my invention is to provide an improved driving construction.

My invention will be defined in the claims. 20 In the drawings showing the preferred embodiment of my invention, Figure 1 shows a plan view, and Fig. 2 a sectional view on line $\alpha\alpha$ of Fig. 1.

In automobile-vehicles the motor is usually 25 heavy, and if it is rigidly supported on the vehicle the jars and concussions which it receives from the vehicle passing over inequalities in the road often injure it or strip some of the gears or loosen it from its support and 30 cause the gears to chatter. I avoid these objections in the preferred construction herein described by hanging the motor on a transverse pivot at one side of its center of gravity and also supporting it on a spring connection 35 to the frame, so that the motor may vibrate back and forth on said pivot, and the jars which otherwise would be communicated to the motor will be taken up to a large extent by the spring. I prefer to have the 40 axle upon which the driven vehicle-carrying wheels are mounted integral—that is, continuous throughout its length—instead of divided, for such an integral axle results in a much stronger construction than one in which 45 the axle is divided.

In motor-vehicles it is desirable that both driven carrying-wheels should not be driven at the same speed when the vehicle rounds a corner, as the inside wheel would "skid," 50 and if compensating mechanism is used to automatically drive the outside wheel while allowing the inside wheel to revolve slowly

or not at all the driven axle could be divided into two parts which can be independently rotated. This is a weak construction. In 55 my invention, however, I have provided a construction by which the axle upon which the vehicle-carrying wheels are mounted may be integral and yet in which such a compensating mechanism is interposed between the 60 motor and the carrying-wheels to drive the same independently, as stated above.

In the preferred embodiment of my invention herein disclosed, 1 2 are longitudinal runners forming part of the frame of the vehicle. The axle 3, preferably the rear one, is mounted in the frame and is preferably integral—that is, continuous throughout its length. The vehicle-carrying wheels 4 5 are mounted on the ends of the axle. I prefer to 70 have the axle fixed to the frame—that is, not rotatable therein—and to allow both said wheels to rotate freely thereon. 6 and 7 are gear-wheels fixed to the said carrying-wheels.

8 9 represent the source of power or motor, 75 in the embodiment illustrated consisting of a pair of steam-engines whose piston-rods 10 and 11 are connected to the cranks of a driven shaft 12.

13 is a driving-wheel keyed to shaft 12, 80 preferably having gear-teeth cut thereon.

The engines are hung on the vehicle on a pivot transverse of—that is, not perpendicular to—and preferably parallel to the wheel-base and at one side of the center of gravity 85 of the engines, preferably as far removed therefrom as possible, so that the pivot will support only a small part of the weight of the motor. In the embodiment illustrated I turn trunnions 14 15 on the engine-casing, which 90 lie in pillow-blocks on the runners 1 2 (one of which pillow-blocks is shown at 16) and are held in place by removable caps, one of which is shown at 17. Similar trunnions rest in pillow-blocks in the portions 18 19 of the 95 frame. The motor may be supported, preferably at the other side thereof, by springs 20 21, located above and below a cross-piece 22 of the vehicle-frame, so that motion of the motor either up or down is resisted by the 100 springs. The driven shaft 12 is preferably concentric with and rotates in the trunnions. The driving-wheel 13 vibrates with the motor and is preferably, but not necessarily, also

concentric with the pivot on which the engine is hung.

In order to transmit the motive power to the carrying-wheels, so that they may be driven substantially independently, I have in this embodiment provided a compensating mechanism having a pair of independently-rotatable wheels, each of which is preferably mounted on an independent division of a shaft and connected to the carrying-wheels to drive the same independently. This compensating mechanism in this embodiment includes a gear-wheel 23, meshing with driving-wheel 13 and fixed to the gear-case 24, which carries one or more bevel-gears 25, Fig. 2, each freely rotatable on a stud (not shown) fixed to the gear-case. Independently-rotatable bevel gear-wheels 26 and 27 mesh with the gears 25 and transmit motion to the carrying-wheels 4 and 5. I preferably key the gears 26 and 27 to the ends of independent divisions 28 29 of a shaft journaled in the frame, and these divisions may carry gears 30 31, which mesh with the gears 6 and 7. 25 When the vehicle travels in a straight line, the bevel-gears 25 do not rotate on their studs, but are carried around with the gear-case and rotate both wheels 26 27 at the same time; but when one of the carrying-wheels is held—for instance, the inside wheel when the vehicle rounds a curve—the gears 25 rotate on their studs and drive the other carrying-wheel faster.

The point of contact between driving-wheel 13 and wheel 23 will not change, no matter how far the motor rocks on its pivot, as the driving-wheel is in this embodiment concentric with that pivot, and in order to keep the center of wheel 23 at a fixed distance from the center of the driving-wheel 13 I may have a pair of distance-pieces 32 33, attached by pins 34 to projections from the frame, as shown, and through which pass the shaft-divisions 28 29.

45 In the construction illustrated I have provided an integral axle, upon which the carrying-wheels are mounted, and a compensating gear between the motor and carrying-wheels for driving them independently. This results in a stronger construction than one in which the axle is divided. The motor is spring-supported, and the point of contact between the driving-wheel and the next wheel of the train does not change no matter how far the motor rocks on its pivot, and this keeps the gears in mesh and to a great extent prevents chattering of the gear, which is very objectionable.

I am aware that many changes may be made in the constructions heretofore illustrated and described without departing from the spirit of my invention, and I therefore do not limit myself to the embodiments herein disclosed.

What I claim is—

65 1. In combination a vehicle, a carrying-wheel upon which said vehicle travels, a motor hung on a transverse pivot at one side of

its center of gravity and eccentric to said carrying-wheel, a spring-support for said motor, a driving-wheel concentric with said pivot 70 and driven by said motor and vibrating with said motor on said pivot, a wheel substantially fixed with relation to said motor and transmitting power therefrom to said carrying-wheel and driven by said driving-wheel, and means to hold the centers of said driving-wheel and fixed wheel at a fixed distance from each other.

2. In combination a vehicle, a carrying-wheel upon which said vehicle travels, a motor hung on a transverse pivot at one side of its center of gravity, a spring-support for said motor, a driving-wheel driven by said motor and eccentric to said carrying-wheel but substantially concentric with said pivot, and a 85 connection between said driving-wheel and said carrying-wheel to drive the latter.

3. In combination a vehicle, a carrying-wheel upon which said vehicle travels, a motor hung on a transverse pivot at one side of 90 its center of gravity, a spring-support for said motor, a geared driving-wheel driven by said motor and eccentric to said carrying-wheel but substantially concentric with said pivot, and a connection between said driving-wheel 95 and said carrying-wheel to drive the latter.

4. In combination a vehicle, a carrying-wheel upon which said vehicle travels, a motor hung on a transverse pivot at one side of its center of gravity, a spring-support for said 100 motor, a driving-shaft driven by said motor and eccentric to said carrying-wheel but substantially concentric with said pivot, and a connection between said driving-shaft and said carrying-wheel to drive the latter.

5. In combination a vehicle, a carrying-wheel upon which said vehicle travels, a motor hung on a transverse pivot at one side of its center of gravity, a spring-support for the other side of said motor, a driving-shaft 110 driven by said motor and eccentric to said carrying-wheel but substantially concentric with said pivot, and a connection between said driving-shaft and said carrying-wheel to drive the latter.

6. In combination a vehicle, a plurality of independently-rotatable carrying-wheels located on either side of said vehicle and upon which said vehicle travels, a motor hung on a transverse pivot at one side of its center of gravity, a spring-support for said motor, a driving-wheel driven by said motor and eccentric to said carrying-wheels but substantially concentric with said pivot, and a connection between said driving-wheel and said 120 carrying-wheels to drive the latter, said connection including a compensating train to automatically rotate one of said carrying-wheels when the other one is held.

7. In combination a vehicle having a frame 130 and an integral axle, a carrying-wheel on each end of said axle, at least one of which wheels is rotatable thereon, a motor pivoted at one side of its center of gravity on a transverse

pivot eccentric to said carrying-wheel and spring-supported from said frame, compensating mechanism located between said motor and carrying-wheels and including a pair of independently-rotatable wheels rotated by

5 said motor, and connections between said latter wheels and carrying-wheels, whereby, when one of said carrying-wheels is held, the power of said motor is automatically applied 10 to rotate the other wheel.

8. In combination a vehicle having a frame and a fixed integral axle, a carrying-wheel on each end of said axle and rotatable thereon, a motor pivoted at one side of its center of 15 gravity on a transverse pivot eccentric to said carrying-wheel and spring-supported from said frame, compensating mechanism located between said motor and carrying-wheels and including a pair of independently-rotatable 20 wheels rotated by said motor, and connections between said latter wheels and carrying-wheels, whereby, when one of said carrying-wheels is held, the power of said motor is automatically applied to rotate the other 25 wheel.

9. In combination a vehicle having a frame and an integral axle, a carrying-wheel on each end of said axle, at least one of which wheels is rotatable thereon, a motor pivoted at one 30 side of its center of gravity on a transverse pivot eccentric to said carrying-wheel and spring-supported from said frame, compensating mechanism located between said motor and carrying-wheels and including a pair 35 of independently-geared wheels rotated by said motor, and geared connections between said latter wheels and carrying-wheels, whereby, when one of said wheels is held, the power of said motor is automatically applied 40 to rotate the other wheel.

10. In combination a vehicle having a frame and a fixed integral axle, a carrying-wheel on each end of said axle and rotatable thereon, a motor pivoted at one side of its center of 45 gravity on a transverse pivot eccentric to said carrying-wheel and spring-supported from said frame, compensating mechanism located between said motor and the carrying-wheels and including a pair of independently-rotatable 50 geared wheels rotated by said motor, and geared connections between said latter wheels and carrying-wheels, whereby, when one of said wheels is held, the power of said motor is automatically applied to rotate the other 55 wheel.

11. In combination a vehicle having a frame and an integral axle, a carrying-wheel on each end of said axle, at least one of which wheels is rotatable thereon, a motor pivoted at one 60 side of its center of gravity on a transverse pivot eccentric to said carrying-wheel and spring-supported from said frame, compensating mechanism located between said motor and carrying-wheels and including a divided 65 shaft, the divisions of which may be independently rotated by said motor, and connections between said divisions of said shaft and

said carrying-wheels, whereby, when one of said carrying-wheels is held, the motive power is automatically applied to said other wheel 70 to rotate the same.

12. In combination a vehicle having a frame and an integral axle, a carrying-wheel on each end of said axle, at least one of which wheels is rotatable thereon, a motor pivoted at one 75 side of its center of gravity on a transverse pivot eccentric to said carrying-wheel and spring-supported from said frame, compensating mechanism located between said motor and carrying-wheels and including a divided 80 shaft, the divisions of which may be independently rotated by said motor, a geared wheel on each division of said shaft, and geared connections between said wheels on said shaft and said carrying-wheels, whereby, when one 85 of said carrying-wheels is held, the motive power is automatically applied to said other wheel to rotate the same.

13. In combination a vehicle having a carrying-wheel, a motor carried by said vehicle 90 and hung on a transverse pivot at one side of its center of gravity, a spring-support for said motor, a driving-wheel driven by said motor and eccentric to said carrying-wheel but substantially concentric with said pivot, a connection between said driving and carrying wheels including a wheel engaging with said driving-wheel, and means holding the centers of said last two wheels substantially at a fixed distance from each other. 100

14. In combination a vehicle having a carrying-wheel, a motor carried by said vehicle and hung on a transverse pivot at one side of its center of gravity, a spring-support for the other side of said motor, a driving-wheel 105 driven by said motor and eccentric to said carrying-wheel but substantially concentric with said pivot, a connection between said driving and carrying wheels including a wheel engaging with said driving-wheel, and means holding the centers of said last two wheels substantially at a fixed distance from each other. 110

15. In combination a vehicle having a carrying-wheel, a motor carried by said vehicle 115 and hung on a transverse pivot at one side of its center of gravity, a spring-support for said motor, a geared driving-wheel driven by said motor and eccentric to said carrying-wheel but substantially concentric with said pivot, a 120 connection between said driving and carrying wheels including a geared wheel meshing with said driving-wheel, and means holding the centers of said last two wheels substantially at a fixed distance from each other. 125

16. In combination a vehicle having a fixed integral axle, a carrying-wheel at each end of the same and rotatable thereon, a motor carried on said vehicle and hung on a transverse pivot at one side of its center of gravity, a 130 spring-support for said motor, a geared driving-wheel driven by said motor and eccentric to said carrying-wheels but substantially concentric with said pivot, a geared connection

located between said driving-wheel and carrying-wheels, a geared wheel meshing with said driving-wheel, and means holding the centers of said last two wheels at substantially a fixed distance from each other, said geared connection including a compensating mechanism having a pair of wheels independently rotatable by said motor and connected with said carrying-wheels, whereby, when one of said carrying-wheels is held, the motive power is automatically applied to the other carrying-wheel to rotate the same.

17. In combination a vehicle having a fixed integral axle, a carrying-wheel at each end of the same and rotatable thereon, a motor carried on said vehicle and hung on a transverse pivot at one side of its center of gravity, a spring-support for said motor, a geared driving-wheel driven by said motor and eccentric to said carrying-wheels but substantially con-

centric with said pivot, a geared connection located between said driving-wheel and carrying-wheels, a geared wheel meshing with said driving-wheel, and means holding the centers of said last two wheels at substantially a fixed distance from each other, said geared connection including a compensating mechanism having a divided shaft provided with a pair of wheels fixed thereon and independently rotated by said motor and geared to said carrying-wheels, whereby, when one of said carrying-wheels is held, the motive power is automatically applied to the other carrying-wheel to rotate the same.

Signed at New York, N. Y., this 17th day of September, 1901.

HARRY J. MARKS.
